UNITED STATES PATENT OFFICE.

MARCUS SMITH, OF TORONTO, ONTARIO, CANADA, ASSIGNOR TO GEORGE A. TUDHOPE,
OF TORONTO, ONTARIO, CANADA.

HEATING APPARATUS.

Application filed November 15, 1919. Serial No. 333,222.

To all whom it may concern:

Be it known that I, MARCUS SMITH, of the city of Toronto, in the county of York, Province of Ontario, Canada, have invented 5 certain new and useful Improvements in Heating Apparatus, of which the following is a specification.

This invention relates to means for increasing the efficiency of the well-known 10 furnaces employed in the heating of buildings, which are provided with internal flues for the products of combustion and spaces for the fluid to be heated bounded by the outer wall.

15 In general the principle of operation involved in the construction of my improvements is to lead the hot products of combustion in a stream moving continuously in one direction between an outer supplemental 20 casing and the outer wall of the furnace, and then lead them through a special flue or flues to the smoke pipe.

The apparatus is hereinafter more fully 25 described and illustrated in the accompanying drawings in which

Fig. 1 is a side elevation of the heating apparatus constructed in accordance with my invention, parts being shown in section;

Fig. 2 a plan view with the top of the 30 outer casing removed;

Fig. 3 a section on the line 3—3 in Fig. 1 looking down, the furnace itself being shown in plan;

Fig. 4 a similar view to Fig. 3 showing 35 a modification; and

Fig. 5 a similar view to Fig. 3 showing another modification.

In the drawings like numerals of reference indicate corresponding parts in the different figures.

1 is a fluid heating furnace of ordinary construction with horizontal sections, though my invention is, of course, applicable to other types of furnace. This heater, 45 it will be seen, is of the type in which internal flues are provided and spaces for the fluid to be heated externally bounded by the wall of the furnace. 2 is the smoke outlet of the furnace. The furnace is surrounded by an external casing of metal or 50 some refractory material, which is made completely air tight. Asbestos board is found to be a suitable material. Preferably the arrangement of the external casing is 55 such that the front of the boiler with its

doors is exposed. The external casing is preferably rectangular in plan and is spaced from the wall of the furnace as indicated more particularly in the plan and sectional views. The spacing between the exterior 60 casing and the wall of the furnace forms a substantially unobstructed passage for the products of combustion, into which passage the smoke outlet of the furnace opens.

Above the top of the furnace is formed a 65 chamber 4, which chamber is separated from the jacket space 5 by the partition 6. The chamber 4 is provided with a smoke collar 7 for connection with the usual smoke pipe leading to the chimney. In the partition 6 70 is formed an opening controllable by the sliding damper 8. When this damper is opened direct draft is provided to the chimney. When the damper is closed, the products of combustion pass to the jacket space 75 5 and thence through flues constructed as hereinafter described. These return flues 9 communicate at their lower ends with the jacket space 5 and at their upper ends with the chamber 4, so that when the 80 damper 8 is closed the products of combustion pass through the jacket space 5, which is entirely free of baffles of all kinds, thence into the return flues 9 and into the chamber 5, from which they pass to the chimney. 85 The return flues might be located outside the casing 3 as shown in Fig. 5, but the simplest and cheapest plan is to form these flues by means of partitions 10 extending across the angles of the casing as shown in Figs. 2, 3 90 and 4 of the drawings. These flues communicate with the chamber 4 through suitably-shaped openings in the partition 6.

This construction lends itself readily to the formation of a more or less complete 95 dead air jacket to prevent radiation through the walls of the external casing. For example, as shown in Fig. 4, partitions 11 may be extended between the partitions 10 forming dead air spaces 12, and partitions 13 parallel to the partitions 10 forming dead air 100 spaces 14.

In order to prevent too strong a draft through the return flues nearest to the smoke collar 7, I may find it preferable to 105 employ baffles 15 in the chamber 4, which will obstruct to a considerable extent the direct passage of products of combustion from the rear flues to the smoke collar.

It will be seen that the construction de- 110

scribed is very simple and is applicable to any shape of boiler with a minimum of labor, since none of the parts involved in the invention, except the front wall of the casing, require to be fitted in any way to the sides of the boiler. As there are no baffles located in the jacket space 5 and the flues 9 are open at the bottom, the surface over which the products of combustion pass are easily cleaned and soot and dust withdrawn through clean-out doors 16 located at the bottom of the external casing.

What I claim as my invention is:—

- 15 1. The combination with an existing water heating furnace complete in itself and provided with an outer wall, with internal flues, with a smoke outlet, and with water spaces, of an external supplemental casing spaced from the furnace wall forming a 20 jacket space between said furnace wall and said external casing into which jacket space the smoke outlet of the furnace opens, said jacket space being substantially unobstructed so that the products of combustion may 25 follow substantially direct paths through said jacket space; a plurality of flues entirely independent of the furnace wall, one end of each communicating with the jacket space aforesaid at a point distant from the smoke outlet of the furnace, whereby the wall of the furnace is jacketed with products of combustion moving substantially without reversal of direction of movement to the flue communications aforesaid; a smoke collar 30 for connection with a smoke pipe adapted to lead to a chimney; a chamber between said smoke collar and flues; and a damper controlled direct communication between the upper part of the aforesaid jacket space and the said chamber.

- 40 2. The combination with an existing water heating furnace complete in itself and provided with an outer wall, with internal flues, with a smoke outlet, and with water spaces, of an external supplemental casing spaced from the furnace wall forming a jacket space between said furnace wall and said external casing into which jacket space the smoke outlet of the furnace opens, said jacket space being substantially unobstructed and said casing extending above the top of the furnace wall; a transverse partition extending between the sides of the external casing above the furnace wall forming a separate chamber over the furnace, said chamber having a damper controlled opening communicating with the jacket space aforesaid and a smoke collar for connection with a smoke pipe; and a 50 flue independent of the furnace wall communicating with said chamber and with the

said jacket space at a point remote from the smoke outlet of the furnace.

3. A furnace constructed as set forth in claim 1 in which each flue is partly formed by part of the external casing.

4. The combination with an existing water heating furnace provided with an outer wall, with internal flues, with a smoke outlet and with water spaces, of an external supplemental casing spaced from the furnace wall forming a jacket space between said furnace wall and said external casing into which jacket space the smoke outlet of the furnace opens, said jacket space being substantially unobstructed so that the products of combustion may follow substantially direct paths through said jacket space; a plurality of flues entirely independent of the furnace wall, one end of each communicating with the jacket space aforesaid at a point distant from the smoke outlet of the furnace, whereby the wall of the furnace is jacketed with products of combustion moving substantially without reversal of direction of movement to the flue communications aforesaid; a common chamber partly formed by part of the external casing and with which each flue communicates; a smoke collar leading from said chamber; and a damper controlled direct communication between the upper part of the aforesaid jacket space and the smoke pipe.

5. A furnace constructed as set forth in claim 1, the external casing being rectangular, and the flues partly formed by partitions extending between adjacent sides of the casing adjacent to the vertical corners of the casing inside the same.

6. A furnace constructed as set forth in claim 1, the external casing being rectangular, and the flues partly formed by partitions extending between adjacent sides of the casing adjacent to the vertical corners of the casing inside the same, and provided also with other partitions extending between the corner partitions to form dead air spaces next to the sides of the casing.

7. A furnace constructed as set forth in claim 1, the external casing being rectangular, and the flues partly formed by partitions extending between adjacent sides of the casing adjacent to the vertical corners of the casing inside the same, and provided also with other partitions extending between adjacent sides of the casing adjacent to the corners and forming dead air spaces in said corners.

Signed at Toronto this 5th day of November 1919.

MARCUS SMITH.
